UNITED STATES PATENT OFFICE

165,118

WALL SHELF

Karin Gunnel Birgitta Strinning and Nils Erik
Strinning, Alvsjo, Sweden

Application July 11, 1950, Serial No. 11,080
In Sweden January 19, 1950

Term of patent 14 years

(Cl. D33—3)

To all whom it may concern:

Be it known that we, Karin Gunnel Birgitta Strinning and Nils Erik Strinning, both citizens of the Kingdom of Sweden, both residing at Alvsjo, Sweden, have invented a new, original, and ornamental Design for a Wall Shelf, of which the following is a specification, reference being had to the accompanying drawing, forming part thereof.

Fig. 1 is a perspective view of a wall shelf, showing our new design; and

Fig. 2 is a side elevational view thereof.

We claim:

The ornamental design for a wall shelf, substantially as shown.

KARIN GUNNEL BIRGITTA STRINNING.
NILS ERIK STRINNING.
